UNITED STATES PATENT OFFICE.

HERMAN KOESTER, OF WATERBURY, CONNECTICUT, ASSIGNOR TO THE BRISTOL COMPANY, OF WATERBURY, CONNECTICUT, A CORPORATION OF CONNECTICUT.

ELECTRICAL LOUD-SPEAKING RECEIVER.

Application filed June 19, 1922. Serial No. 569,332.

To all whom it may concern:

Be it known that I, HERMAN KOESTER, a citizen of the United States, and a resident of Waterbury, in the county of New Haven and State of Connecticut, have invented certain new and useful Improvements in Electrical Loud-Speaking Receivers, of which the following is a specification.

10 The invention relates to electrical receiver apparatus for amplifying sounds, such receiver device being generally termed "loud speaking receivers." The invention relates more particularly to that type of loud 15 speaker receivers in which the one end of the actuating lever is not fixedly secured to the diaphragm of the receiver but is tensioned thereby; and in which the actuating lever is substantially of one piece and fulcrumed on one of the poles of the permanent 20 magnet of the receiver and under the traction of the other.

It has for its object, in a receiver of this character, to so associate the diaphragm 25 end of the lever with the diaphragm that the former will be held centrally with respect to the latter. The invention has for its object, also, a specific form of loose connection between the said end of the lever 30 and the diaphragm in case a diaphragm of mica or like material is employed.

The nature of the invention, however, will best be understood when described in connection with the accompanying drawings, 35 in which—

Fig. 1 is a longitudinal section thru the receiver device.

Fig. 2 is a horizontal section taken on the line 2—2, Fig. 1, looking in the direction of the arrows.

Fig. 3 is a transverse section taken on the line 3—3, Fig. 1, looking in the direction of the arrows.

Fig. 4 is an enlarged detail section of the 45 positioning means for the lever; and, Fig. 5 is a sectional detail view of a modification therein.

Similar characters of reference designate 50 corresponding parts thruout the several views.

Referring to the drawings, 10 designates a suitable casing or container wherein the entire apparatus may conveniently be mounted and housed. The device itself comprises 55 a permanent U-shaped magnet 11, one leg

being shorter than the other and having pole pieces 12 and 13 directed at right angles from the ends thereof. The pole piece 13, furthermore, is provided with a solenoid 14 thru which current passes as received from a transmitting apparatus (not shown), and as is well understood. Suitable leads 15 are connected to the said solenoid for this purpose.

The magnet 11, in addition, carries a sound box 16 which is adjustably secured thereto for slight angular motion to tension a lever hereinafter set forth, the adjustment being effected, for example, thru suitable nuts 17 working on the screw 18. A nut 19 serves to secure the sound box and attached magnet to the casing 10; and an outlet 20 extends therefrom thru the said cover and may receive a suitable horn 21 or other amplifying member.

In order to effect the amplification, the diaphragm 22 of the sound box is to be vibrated in accordance with the pulsations received from the transmitting circuit 15, the diaphragm being held securely in the sound box 16, by rubber washers 23 or the like, in the usual manner. These pulsations affect the magnetic attraction of the pole piece 13 for the armature end of a free, one-piece lever 24 whose other end is associated with the diaphragm 22 which is caused to bear thereon under a predetermined tension in accordance with the normal attraction of the pole piece 13 for its corresponding end. The lever 24, moreover, is fulcrumed on the other pole piece 12, merely resting thereon; but is guided against lateral displacement by means of ears 25 downwardly directed from the sides of the lever and embracing the said pole piece.

In the case of a lever of this type, if its diaphragm end has been rigidly attached to the diaphragm, the latter thru this positive connection is more or less distorted in the operation of the lever, especially should its position on the fulcrum pole piece become somewhat displaced. In accordance with the present invention, a connection between lever and diaphragm is provided which will insure perfect freedom of movement of both and yet permit the proper transmission of the vibrations of the lever to the said diaphragm. Furthermore, in the case of a loose connection between lever and diaphragm, unless the latter be arranged to

be maintained centrally with reference to the diaphragm, distortions of the latter will also occur. In order to overcome such effect, the end of the lever is arranged to be positively guided by the diaphragm and to axially move same, although permitting otherwise of perfect freedom of movement of the one with respect to the other.

For example, as indicated in the drawings, the diaphragm may be centrally perforated and a grommet or eyelet 30 inserted, especially in the case of diaphragms of such material as mica having laminations which would tend to split along the edge of the perforation and thus destroy the effect of the diaphragm. It is desirable, in the case of the diaphragms of this type, to include between the faces of the diaphragm and the heads of the grommet or eyelet washers 31 of suitable material such as paper, the same being held or pinched to the diaphragm by the heads of the grommet. The diaphragm end of the lever is preferably reduced in this case and fits loosely into the grommet, as shown; and a curved shoulder 32 is provided thereon below the lower head of the grommet and designed to conform substantially to the curvature of same. Moreover, it forms therewith substantially a ball and socket joint, so that the angular movement of the lever and any slight variation in adjustment of the lever relative to its fulcrum may be accommodated without causing distortion of the diaphragm, and whereby the resulting reproduction of the sound is of the highest quality.

In Fig. 5, a means of centering the lever with reference to the diaphragm has been indicated, the same being more especially suitable for metal and like diaphragms in which an indentation or recess 33 may be provided for the end 34 of the lever and which is preferably rounded to afford the desired freedom of movement.

I claim:

1. In an electrical loud speaking receiver: a permanent magnet, a perforated diaphragm, and a lever having one end under

the influence of said magnet, the other end fitting thru the perforation of the diaphragm, unsecured thereto and bearing against one side only of the latter.

2. In an electrical loud speaking receiver: a permanent magnet, a centrally perforated diaphragm, and a lever having one end under the influence of said magnet, the other end fitting thru the perforation of the diaphragm, unsecured thereto and bearing against one side only of the latter.

3. In an electrical loud speaking receiver: a permanent magnet, a perforated mica diaphragm, a grommet fitting the perforation of the diaphragm and washers mounted about the grommet and held thereby between the opposite faces of the diaphragm and the heads of the grommet, and a lever having one end under the influence of said magnet, its other end fitting into said grommet and bearing against one head only of said grommet.

4. In an electrical loud speaking receiver: a permanent magnet, a perforated diaphragm, a grommet fitting the perforation of the diaphragm, and a lever having one end under the influence of said magnet, the other end being reduced and fitting into said grommet and having a curved shoulder to fit the corresponding grommet head to provide a movable joint therewith.

5. In an electrical loud speaking receiver: a permanent magnet, a centrally perforated mica diaphragm, a grommet fitting the perforation of the diaphragm and paper washers mounted about the grommet and held thereby between the opposite faces of the diaphragm and the corresponding heads of the grommet, and a lever having one end under the influence of said magnet, the other end being reduced and fitting into the grommet and having a curved shoulder to fit the corresponding grommet head to provide a movable joint therewith.

Signed at Waterbury, in the county of New Haven and State of Connecticut, this 14th day of June, A. D. 1922.

HERMAN KOESTER.
